TWISTING MECHANISM FOR WARP TWISTING-IN MACHINES

Filed Jan. 17, 1928

INVENTOR.
John H. Becker,
BY
John Edward,
ATTORNEY.

UNITED STATES PATENT OFFICE.

JOHN HENRY BECKER, OF RICHMOND HILL, NEW YORK, ASSIGNOR TO WARP TWISTING-IN MACHINE COMPANY, OF BROOKLYN, NEW YORK, A CORPORATION OF NEW YORK.

TWISTING MECHANISM FOR WARP TWISTING-IN MACHINES.

Application filed January 17, 1928. Serial No. 247,336.

In machines for joining two warp threads by a twist it is known to employ two coacting members one of which rotates in face to face contact with the other and to support the two threads so that they project toward each other from supply beams and then, after extending around suitable guides, so that their ends project in the same direction; whereby when the rotary member rotates the two members will first coact to twist said ends around each other and then to twist them as an already twisted unit around one of the threads. Each member usually consists of a support and a pad, the latter affording its twisting face and being yieldable. (See my Patent No. 1,424,276, for example.)

The present invention consists in a twisting member of the class indicated in which the pad is yieldingly arranged on its support in a novel manner and so as to permit adjustment of the pressure to be exerted on the threads.

The invention further consists in an improved construction of a knife for cutting away the terminals of said ends of the two threads.

In the drawing,

Fig. 1 is a section on line 1—1, Fig. 2;

Fig. 3 is a plan;

Fig. 4 is an inside view of the pad support of the fixed member;

Fig. 5 is a section on line 4—4, Fig. 3; and

Fig. 6 is a detail illustrating the knife.

A—A are the threads projecting toward each other from supply beams 1 (diagrammatically shown) and extending around guides 2—2, B—B being their ends projecting in the same direction to a clamp 3 and also received by a fork 3^a.

The rotary twisting member comprises a support 4 and a twisting pad 5 having headed devices 5^a by which it is removably held in notches 4^a in said support, which is the segmental head of a suitably journaled shaft 6. The fixed twisting member comprises a support 7 and a twisting pad 8 having headed devices 8^a by which it is removably held in notches 7^a in said support, said support 7 being a segmental head of an arm 9 rigidly secured to a fixed shaft 10 parallel with shaft 6. Support 7 may carry the fork 3^a as shown. The guides 2 project through a hole in support 7 so that the threads engage them inwardly of the acting face of pad 8,

i. e., lie in such a vertical plane that they will be between the two pads when the rotary member is in motion, whereby thereupon said rotary member will first coact with the fixed member to twist the ends B—B together (after they have been severed, as will appear) as it rotates against the other member with said ends intervening between them—such ends swinging around guides 2—2 and then twist the thus twisted ends as a unit around the body parts A—A of said threads, thus completing the twisting and joining of the threads.

Pad 8 is yieldingly backed or supported as follows: A groove 11 is formed in the inner face of support 7 and receives a plate-spring 12, normally arched and projecting from the groove (Fig. 4) and being the head of a stem 13 which extends through a hole in the support and has tapped into its free end a screw 14 whose head may bear against the support. Said hole is here the bore of a tubular post 15 secured to support 7 and the head bears against a spring split lock-washer 16 interposed between it and the post. Thus the spring is in effect a cushion for the pad spacing it from the support, and the screw affords means to variably tension the spring and thereby vary the spacing it tends to maintain between the pad and support, and consequently between such pad and the pad 5 according to the thickness and other qualities of the threads being twisted together. Usually there will be two of these adjustable cushions for the pad, one near each radial side of the support 7. It will be understood that the interlocks at 5^a and 8^a permit movement of the pad toward and from the support 7.

At the outset of the twisting a knife operates to sever the ends B—B between 2 and 3. This knife includes a holder 17 oscillating in a bracket 18 attached to support 7 and a blade 19 carried by the holder. The holder has a cross-groove 20 receiving the blade flatwise therein, which is removably held in place by a headed stud in the form of a screw 21 extending through a key-hole slot 22 in the blade. In fitting the blade to the holder the larger end of the slot is made to admit the screw-head, then the blade is slid along until the screw occupies the narrow part of the slot, and finally the screw is turned to clamp the blade between its head and the

holder. Thus the blade may be securely held and still it is easily applied and removed.

Having thus fully described my invention, what I claim is:

- 5 1. In a twisting mechanism of the class described, a twisting member comprising a support, a twisting pad carried thereby and movable toward and from the same, a cushioning spring for the pad spacing the same from the support, and means to variably tension the spring and thereby vary the spacing it tends to maintain between the pad and support.
- 15 2. In a twisting mechanism of the class described, a twisting member comprising a supporting element, a twisting pad element carried thereby and movable toward and from the same, a cushioning spring for the pad element spacing the same from the supporting element and having a stem penetrating one 20 of them, and a screw tapped into said stem and having a bearing on the last-named element.
- 25 3. In a twisting mechanism of the class described, a twisting member comprising a supporting element, a twisting pad element carried thereby and movable toward and from the same, a normally arched cushioning plate spring for the pad element spacing the same from the supporting element and having a

stem penetrating one of them, and a screw 30 tapped into said stem and having a bearing on the last-named element.

4. A knife for the purpose described comprising a holder having a groove therein and a headed stud projecting therefrom, and a 35 flat blade received flatwise in the groove and having a slot of varying width receiving the stud at its lesser width, the head of the stud being wider than such lesser width and narrower than the greater width of the slot and 40 the blade being shiftable lengthwise of said slot to bring its greater width into registry with the head and thereby permit removal of the blade.

5. A knife for the purpose described comprising a holder having a groove therein and a headed clamping screw tapped into the same, and a flat blade received flatwise in the groove and having a slot of varying width receiving the stud at its lesser width, the head 50 of the screw being wider than such lesser width and narrower than the greater width of the slot and the blade being shiftable lengthwise of said slot to bring its greater width into registry with the head and thereby 55 permit removal of the blade.

In testimony whereof I affix my signature.

JOHN H. BECKER.
